WASHING MACHINE

Anton C. Schmelzer, Cleveland, Ohio

Application November 29, 1939, Serial No. 306,590

4 Claims. (Cl. 74—606)

This invention relates in general to washing machines for domestic use and more particularly to so-called combination washing machines embodying a washing compartment and a drying compartment for centrifugally extracting water from articles washed in the washing compartment, and has for its principal objects the provision of a compact, economically constructed and highly efficient washing machine of the type referred to, which machine embodies new, improved and simplified operating mechanism for effecting washing and drying operations, new, improved and simplified mechanism for starting the operating mechanism for both the washing and drying operations, and new and improved construction of the washing and drying compartments permitting connection of these compartments to a unitary structure of utmost rigidity and simplicity.

In addition the invention has other marked improvements and superiorities which radically distinguish it from presently known combination washing machines. These improvements or superior characteristics embodying certain novel features of construction and combination of parts and certain new steps in uniting specifically built washing and drying compartments to a unitary structure are clearly set forth in the following specification and the appended claims; and a preferred form of embodiment of the invention is hereinafter shown with reference to the accompanying drawings forming part of the specification.

In the drawings:

Fig. 1 is a longitudinal sectional view through a combination washing machine according to the invention, the section being taken on line 1—1 of Fig. 2.

Fig. 2 is a plan view of the combination washing machine shown in Fig. 1.

Fig. 3 is a fragmentary sectional view through one end of the combination washing machine, the section being taken on line 3—3 of Fig. 2.

Fig. 4 is a fragmentary sectional view through the middle portion of the combination washing machine, the section being taken on line 4—4 of Fig. 2.

Figs. 5 through 7 are fragmentary sectional views of the upper portions of the washing and drying compartments and the bracket interconnecting these compartments, thus

Fig. 5 is a fragmentary sectional view through the washing compartment,

Fig. 6 a sectional view through the connecting bracket, and

Fig. 7 a fragmentary sectional view through the drying compartment.

Fig. 8 is a fragmentary sectional view through the flanged upper portion of the washing compartment, the section being taken on line 8—8 of Fig. 2.

Fig. 9 is a perspective view of a stiffening bracket for the flanges of the washing and drying compartments.

Fig. 10 is a perspective view of the connecting bracket for the washing and drying compartments.

Fig. 11 is an enlarged horizontal sectional view through the gear box structure of the washing machine shown in Fig. 1, the section being taken on line 11—11 of said Fig. 1.

Fig. 12 is a vertical sectional view through the gear box structure of the washing machine, the section being taken on line 12—12 of Fig. 11.

Fig. 13 is another vertical sectional view through the gear box structure of the combination washing machine, the section being taken on line 13—13 of Fig. 11.

Fig. 14 is a horizontal sectional view through a somewhat modified and simplified gear box structure for the combination washing machine.

Fig. 15 is a fragmentary sectional view partly in elevation showing the adjustable attachment of the modified gear box structure of Fig. 14 to the frame or base member of the combination washing machine.

Fig. 16 is a vertical sectional view through the modified gear box structure shown in Fig. 14, the section being taken on line 16—16 of said figure.

Fig. 17 shows a diagrammatic view of the operating mechanism for the washing compartment and

Fig. 18 a similar diagrammatic view of said mechanism in another working position.

Figs. 19 and 20 are sectional views through the clutch mechanism for effecting a slip coupling of the dryer with the motor, thus

Fig. 19 shows a sectional view through the male member of a cone-clutch and

Fig. 20 a sectional view through the female member of said cone-shaped clutch and the mercury slip clutch coupled with said female member and the motor.

Fig. 21 is a sectional view through the clutch coupling connecting the agitator of the washing machine compartment with its operating mechanism.

Fig. 22 is a plan view of a one lever operated

mechanism for both the washing machine and dryer mechanism.

Fig. 23 is a front view of the one lever operated controlling mechanism shown in Fig. 22, and

Fig. 24 is a fragmentary side view of the operating handle member and its coupling with the one lever operated controlling mechanism shown in Figs. 22 and 23.

Referring now more particularly to the drawings, reference numeral 2 denotes a flanged base member supported on legs 3 riveted or otherwise suitably secured to the peripheral flange or wall 4 of said base member. Base member 2 has arranged in its top face 5 circular recesses 6 and supports in these recesses cylindrically shaped, flanged tubs 7 and 8, which tubs form the washer and dryer compartments and are rigidly secured to each other and base member 2 in a manner hereinafter to be described.

Washing operations in the washing compartment are effected by means of an oscillatory agitator 9 mounted for movement about a vertical shaft 9', and drying operations in the drying compartment are effected by means of a cone-shaped clothes basket 10 rotatably mounted in said compartment upon a basket drive shaft 11 in said compartment and consisting of upper and lower portions 12 and 13 respectively. Portions 12 and 13 are formed with outwardly extending flanges 14 and 15 secured together in slightly spaced relation by means of rivets 16 so as to form arcuate slots 17 between said portions and permit of escape of water from basket 10 during drying operations. The vertical shaft 9' and the basket drive shaft 11 are driven by a motor 18 supported below base member 2 and connected in driving relation to said shafts in a manner hereinafter to be described.

The clothes rinsing apparatus including the above referred to double cone-shaped clothes basket 10 is substantially constructed in the manner disclosed in my Patent No. 2,074,866 dated March 23, 1937. Thus the basket drive shaft 11 which projects through an opening in base member 2 into a flanged gear box 19, in turn secured as at 20 to the flange 4 of said base member, has its lower end 21 journaled in ball bearings 22 mounted in a cup-shaped extension 23 of said gear box, and has its upper portion 24 journaled in ball bearings 25 mounted on a tube 26, which tube is rigidly secured to the gear box 19 and the base member 2.

The upper end of the thus rotatably mounted basket drive shaft 11 mounts a cone-shaped male adapter 27, rigidly fixed to said shaft, and this adapter co-operates with a cone-shaped female adapter 28 suitably secured to lower portion 13 of basket 10 and adapted to sleeve over and snugly receive male adapter 27. As the skirt portion 29 of adapter 27 is outwardly flared or beveled similarly to the adapter 28, a tight removable fit between the parts can be had by merely pressing the clothes basket and its adapter 28 down over the upper end of the shaft 11 and its adapter 27. The lower portion 13 of basket 10 is enclosed within an inner tank or apron 30 which substantially conforms to the configuration of and is spaced from the basket. This apron is fluid tightly secured at its lower, inwardly flanged end 31 to the top of the base member 2 and the upper end 32 of the apron terminates within the downwardly extended flange 15 of clothes basket 10.

Rotation of the basket causes the water to ride up the outwardly flared sides of the lower half 13 of the basket and out through the arcuate slots

17 and then down into tub 8, downwardly extended flanges 14 and 15 effectively preventing any water from entering the space 33 between the apron and the basket, and in consequence all danger of water reaching the ball bearings 22 and 25 is eliminated. Furthermore, the rotation of basket 10 is not retarded by contact with the water and suds extracted from the clothes.

Water thrown from basket 10 passes through 10 a drain 34 of tub 8 to and through a two-way valve 35, the inlet 36 of which is coupled with said drain and the outlet 39 of which is coupled with a pump 40 (a propeller pump being shown, however, any other conventional pump, such as a centrifugal pump, may be used), to said pump and is discharged from the pump through a hose (not shown), all as now generally practiced. Two-way valve 35 has its other inlet 37 coupled with the drain 39 of tub 7 to permit of proper discharge of water from each 20 of the two compartments in accordance with the position of the valve. A horizontal shaft 41 (see Figs. 14 and 16), carrying at its inner end a bevel gear 42, in turn meshing with a bevel gear 43 on the stem 44 of the valve 35, effects proper setting of the valve and such shaft may readily be rotated by a handle (not shown).

The described washing and drying apparatus 30 of the combination washing machine is driven by motor 18 by means of a driving mechanism arranged in flanged gear box 19 so as to effect actuation of the washing and drying apparatus singly or combined. Thus, motor 18, by means 35 of a flexible coupling 45, is coupled with one end of a drive shaft 46, which shaft extends its other end through gear box 19 into a housing 47 of pump 40 and carries a propeller 48 for said pump. Drive shaft 46 is mounted in a bearing 49 and a sleeve member 50, which member is fixedly supported in gear box 19 and carries two bearings 52 and 53 for said shaft 46. In addition, drive shaft 46 mounts a male release clutch member 54 of a release clutch 54' slidably and non-rotatably secured to said shaft and co-operating with a female release clutch member 55 forming an integral part of a spiral gear 56 rotatably mounted on sleeve member 50 by means of bearings 57, 58. A coiled spring 59, compressed between a cup 60 fixed to shaft 46 and the flange 61 of the male release clutch member 54, forces said latter clutch member toward and into engagement with the female release clutch member 55, and thrust washers 62 take up any end thrust on spiral gear 56. This spiral gear meshes with a spiral gear 64 fixed to one end of an idler shaft 65, which latter shaft is mounted at a right angle to shaft 46 and extends below said shaft. Spiral gear 64 is provided with a hub, shaped to form one claw member 66 of a claw clutch 67, and the other end of the idler shaft 65 has fixedly secured there-to the one claw member 68 of a second claw clutch 69.

When motor 18 is running, the drive shaft 46 through release clutch 54' and spiral gears 56 and 64 effects continuous rotation of idler shaft 65, which shaft may be selectively coupled with the mechanism for driving shaft 9' for agitator 9 and drive shaft 11 for double cone-shaped clothes basket 10. The mechanism for driving shaft 9' includes a worm gearing 70 having a worm 71 axially aligned with idler shaft 65 and mounted in bearings 72, 73 and a worm wheel 74 journaled upon a stud shaft 75, which shaft

in turn is fixedly secured to bottom wall 76 of gear box 19. This worm wheel actuates upon a segmental gear 77 having a roller pin 78 fixedly secured to said gear and engaging with its roller 79 an elongated, inverted channel 80 in an extension 81 of segmental gear 77, thus effecting working engagement between worm wheel 74 and segmental gear 77. The teeth 82 of segmental gear 77, which is pivotally mounted on a stud shaft 83 secured to gear box 19, mesh with the teeth 83' of a gear 85 integrally formed at the lower portion of shaft 9'. This shaft is pivotally mounted on a stud shaft 84 secured to gear box 19 and guided in a bearing 84' arranged at the top of a tubing 86, which tubing is rigidly secured to the top plate 87 of said gear box. It should be noted that the channeled extension 81 of segmental gear 77 is angularly related to a line interconnecting the pivot points of worm wheel 74 and segmental gear 77 and that movements of segmental gear 77 in opposite directions are unlike, so that shaft 9' moves with two unlike strokes during each revolution of worm wheel 74. This will best be understood from inspection of the diagrams shown in Figs. 17 and 18. In these diagrams Fig. 17 indicates at A the size of the angle of rotation of worm wheel 74 necessary to effect one of the two opposite movements of segmental gear 77 and Fig. 18 indicates at B the size of the angle of rotation of worm wheel 74 to effect the other one of the two opposite movements of segmental gear 77. It will be seen, that while segmental gear 77 moves through an angle C, the angle of rotation of worm wheel 74 is much larger in Fig. 17 than the angle of rotation B in Fig. 18, so that worm wheel 74, when rotating at constant speed, effects two different movements of segmental gear 77, one being faster than the other. Such movements effect different rotary speed of agitator 9 and materially influence washing operations, as oscillatory movements of different speed and time ratios effect washing action of an agitator and break up undesirable harmonic oscillations of the washing liquid set in motion by the agitator.

Worm 11 can readily be coupled with claw clutch member 66 on the hub of spiral gear 64 by means of its extension 88 mounting the outer end of a collar 89 which is shaped to form the second claw member 90 for claw clutch 67. Collar 89 is slidably and non-rotatably engaged with extension 88 and can readily be shifted by means of a fork 91 pivotally mounted at 92.

The mechanism for driving basket drive shaft 11 includes a shaft 93 axially aligned with idler shaft 65 and mounted in bearings 94 and 95. Shaft 93 carries at its outer end a spiral gear 96 meshing with a spiral gear 97 on basket drive shaft 11, and, in addition, carries at its inner end a collar 98, the outer side of which is shaped to form the second claw member 99 for claw clutch 69. Collar 98 is slidably and non-rotatably engaged with shaft 93 and can readily be shifted for engagement with claw member 68 by means of a fork 100 pivotally mounted at 101.

When motor 18 is running, the described driving mechanism for agitator 9 and clothes basket 10 continuously operates pump 40 and permits of selectively oscillating agitator 9 and rotating clothes basket 10 singly or combined. Shocks caused by coupling operations of claw clutches 67 and 69 or in any other way effect a disengagement of release clutch 54', so as to avoid

strain on motor 18. The arrangement also permits of low rotary starting speed of clothes basket 10, as the elastic form of coiled spring 59 is chosen to permit release of clutch 54' at any overload. It should be stated that any other type of clutches and release clutch may be used for structures shown, provided that such clutches are released in case of shocks or overload.

The cylindrically shaped tubs 1 and 8 are rigidly secured to base member 2, all as generally practiced. These tubs, see Figs. 2 to 10, have their top portions bent outwardly to provide skirtings 102, 103 respectively, which partly surround the tubs and are shaped between the tubs to table-like straight edge top portions 104, 105 respectively, provided with downwardly extended, oppositely arranged flanges 106, 107. A T-shaped bracket member 108 having its web 109 extended between flanges 106, 107 and following at its end 110 the outline of the shape of the skirting covers the gap between top portions 104, 105 and is secured to flanges 106 and 107 by means of screws 111. The described arrangement permits of the construction of a unitary combination machine of utmost rigidity and simplicity, unites the tubs in a simple and economic manner and, additionally, provides a most desirable top plate with very small additional cost.

If desirable, as shown, skirtings 102, 103 can be stiffened by small brackets 112 which preferably are riveted to the skirtings and, in addition, skirting 103 at the outer end of tub 8 may be laterally extended to form an enlarged table-like top 113, preferably ending in a straight edge 114 and covered by an angle bracket or molding 115 secured to the table-like top 113 by means of rivets 116.

In the modified form of driving mechanism for agitator 9 and clothes basket 10 disclosed in Figs. 14 and 16, motor 117 is arranged in axial alignment with and between a worm shaft 118 and a shaft 119 which carries spiral gear 96 meshing with the spiral gear 97 on basket drive shaft 11. Motor 117 is mounted on an elongated U-shaped bracket 120, the two end walls 121 and 122 are secured to individual gear boxes 123, 124 respectively, by means of slots 125. A flexible coupling 126 connects shaft 127 of motor 117 with an extension 128 on worm shaft 118, and this worm shaft drives the driving mechanism for agitator 9. Such driving mechanism is substantially similar to the one described above and is therefore not described. However, in the present case the shaft mounting agitator 9 is split and has arranged between its split shafts 129 and 130 a clutch mechanism for selectively coupling split shaft 130 with split shaft 129. Such clutch mechanism embodies a housing 131' which is mounted on top of gear box 123 by means of screws 132 and has extended thereinto split shaft 129 formed at its lower end with teeth meshing with segmental gear 77. At its top end split shaft 129 has rigidly attached a slotted female coupling member 133 co-operating with a collar-like male coupling member 134 slidably and non-rotatably mounted on split shaft 130 supporting agitator 9. A yoke member 135, fixedly mounted on a shaft 136, in turn pivotally mounted in ear portions 137 on housing 131', effects shifting of collar-like male coupling member 134 toward and away from the female coupling member 133 and thus controls actuation of agitator 9.

The other end of shaft 127 of motor 117 mounts shiftably and non-rotatably connected therewith a release clutch arrangement 138 in

cluding the female clutch member 139 of a cone-clutch 140. This release clutch arrangement (see Fig. 20) embodies a mercury release clutch 141 consisting of a circular housing 142, a rotor 143 in housing 142 and brake shoes 144 radially arranged within housing 142 opposite rotor 143. Brake shoes 144 are forced into frictional engagement with rotor 143 when housing 142 is rotated and mercury within said housing enters by centrifugal force behind these brake shoes. The housing 142 is rigidly attached to a hub 145 which is provided with an enlarged head 146, and head 146 has fixedly secured thereto a collar 147 pressed upon said head. The hub 145 and collar 147 are slidably and non-rotatably secured to shaft 127 by means of a key 148 sliding in a keyway 149 of shaft 127. Rotor 143 of clutch 141 is formed with a laterally extended hub 150 mounting female clutch member 139 which is rigidly fastened to said hub by means of a pin 151. Clutch member 139 co-operates with a male cone clutch member 152 pinned to shaft 119 and this shaft which extends into gear box 124 has secured to its inner end spiral gear 96 meshing with spiral gear 97 on basket drive shaft 11. In operation collar 147 effects shifting of release clutch arrangement 138 toward and away from male cone clutch member 152 and effects throwing in and out of cone clutch 140. When said cone clutch is thrown in, the sudden load on mercury release clutch 141 effects slippage between rotor 143 and housing 142, thus causing slow starting of rotation of the basket and thereafter gradual increase in the rotation of the clothes basket without excessive load on motor 117.

Automatic gradual starting of the rotation of clothes basket 10 is of utmost importance in proper drying operations and avoids overloading of motor 117. Such starting of rotation of basket 10 can be accomplished by any suitable type of clutch, for example by a friction clutch, disc clutch, planimeter drive, etc., the main object of all such release devices being to obtain slow starting of rotation of basket 10 and thereafter gradual increase of the rotary speed of said basket until the speeds of shaft 119 and motor shaft 127 are synchronized.

Preferably, as shown, the driving mechanism is connected to flange 4 of base member 2 by means of ribbed spider arms 154, which arms at their inner ends are secured to gear boxes 123, 124 by means of rivets 155 and carry at their outer ends angle plates 156 adjustably secured to said spider arms and fixedly connected to flange 4 by means of screws 157. Rubber pads 158 arranged between angle plates 156 and wall 4 of base member 2 serve as sound deadening means to eliminate excessive vibration of base member 2. The driving mechanism for agitator 9 and clothes basket 10 is actuated by a single lever operating mechanism, see Figs. 22 and 23. Such operating mechanism is mounted on a plate 159 secured to two of the spider arms 154 by means of bolts 160. The single lever operating mechanism consists of two oppositely arranged symmetrically constructed actuating devices 161, 161', each of which includes a bracket member 162 secured to plate 159 by means of screws 163. Bracket member 162 pivotally supports in elevated bearings 164 and 165 a ratchet mechanism 166 which actuates a cam operated shifting arrangement 168 coupled with the respective clutching device of the driving mechanism as will be later described. Ratchet mechanism 166 embodies a

5 ratchet wheel 169 pivotally supported upon a shaft 170 and a substantially inverted T-shaped ratchet lever 171 also pivotally supported upon said shaft 170. The one horizontal arm 172 of said T-shaped ratchet lever carries a spring 173 pressed ratchet pin 173, the other horizontal arm 174 of lever 171 is yieldingly coupled with bracket 162 by means of a spring 175 and operates with a stop post 176 to avoid undesired movement of said lever, and the vertical arm 177 of ratchet lever 171 is coupled with a single operating lever 178 for the operating mechanism. Ratchet wheel 169 is axially aligned and rigidly connected with a cam 179 of shifting arrangement 168, so as to effect simultaneous rotation of the ratchet wheel 169 and cam 179 when ratchet lever 171 is actuated by operating lever 178. Cam 179 which is slightly larger than ratchet wheel 169 has its peripheral surface provided with a plurality of alternately arranged shallow and deep curved recesses 180 and 181 equal in number to the teeth of ratchet wheel 169 and aligned therewith. The recesses 180, 181 seat a roller 182 on arm 183 of a rocking lever 184, which lever is pinned at 185 to a shaft 186, in turn pivotally mounted in bearing 165 and thus impart oscillatory movements to said shaft 186 when cam 179 is rotated together with ratchet wheel 169 and roller 182 enters from shallow recess 180 into deep recess 181 and vice versa. The rotary movement of shaft 186 of actuating device 161 effects shifting of clutch mechanism 131 by means of a lever 187 secured to shaft 186 and a link 188 connecting lever 187 with a lever 189 on shaft 136 which is fixed to yoke member 135 of clutch mechanism 131, and the movement of shaft 186 of actuating device 161' effects shifting of cone clutch 140 by means of a forked lever 190 secured to shaft 186', which lever engages with its forked end 191 a pin 192 at the end of a lever 193 fixed to a shaft 194, which shaft is mounted in ears 195 on bracket 120 and has fixedly secured thereto a yoke 196 engaging with its rollers 197 in the recess 198 in collar 141.

40 Actuation of ratchet lever 171 by operating lever 178 effects connection and disconnection of clutch mechanism 131 and therewith starting and stopping of agitator 9, clutch mechanism 131 being engaged when roller 182 rests in one of the deep recesses 181 and disengaged when roller 182 rests in one of the shallow recesses 180 in cam 179, and actuation of ratchet lever 171' by said operating lever 178 effects connection and disconnection of cone clutch 140 and therewith starting and stopping of rotation of clothes basket 10, cone clutch 140 being engaged when roller 182' rests in one of the deep recesses 181' and disengaged when roller 182' rests in one of the shallow recesses 180' in cam 179'. To effect individual actuation of the actuating devices 161 and 161' the operating lever 178, pivotally mounted at 199 (see Fig. 24), embodies at its lower end a cross member 200 provided with slots 201, 201', which slots engage with pins 202, 202' on ratchet levers 171, 171' respectively. It should be noted, that pins 202 and 202' engage the slots 201 and 201' in symmetrical places, so as to permit individual actuation of each of the levers 171 and 171' without disturbance of the other ratchet lever and that the rollers 182, 182' on rocking levers 184, 184' are yieldingly forced into engagement with the recesses in cams 179, 179' by springs 203, 203' connected to the ends of rocking levers 184, 184' and plate 159.

Having thus described my invention, what I claim is:

1. In a transmission for washing machines two parallel shafts, a gear box including gearing for one of said shafts, a second gear box including gearing for the other one of said shafts, an elongated U-shaped bracket having its flanges secured to said gear boxes, and an electric motor supported by said bracket, the opposite ends of the shaft of said motor being extended toward the flanges of said bracket and coupled with one of the elements of each of the two gearings.

2. In a transmission for washing machines a gear box including a driven shaft, a second gear box including a driven shaft, an elongated U-shaped bracket with perforated flanges secured to said gear boxes so as to axially align their driven shafts and extend their shafts through the perforations in said flanges, an electric motor supported by said bracket so as to align its shaft with said driven shafts, and means coupling the ends of said motor shaft with the driven shafts.

3. In a transmission for washing machines two parallel shafts, a gear box with gearing coupled with one of said shafts, a second gear box with gearing coupled with the other one of said shafts, 5 an elongated U-shaped bracket spacing said gear boxes and attached with its flanges thereto, an electric motor supported by said bracket to extend its shaft lengthwise of said bracket between said gear boxes, a slip coupling having its two coupling members secured to one end of said motor shaft and a gearing element of the first gear box, and means coupling the other end of the motor shaft with a gearing element of the second gear box.

10 4. A transmission for washing machines as described in claim 2, wherein the driven shaft of one of the gear boxes extends with its both ends through the wall of the gear box for coupling said shaft with said motor and providing a power-20 take off for said gear box.

ANTON C. SCHMELZER.
